UNITED STATES PATENT OFFICE.

JOHN S. SORENSEN, OF MUNCY, PENNSYLVANIA, ASSIGNOR TO SPROUT, WALDRON & COMPANY, OF MUNCY, PENNSYLVANIA, A CORPORATION OF PENNSYLVANIA.

ATTRITION-MILL.

1,146,032.

Specification of Letters Patent. Patented July 13, 1915.

Application filed April 7, 1911. Serial No. 619,621.

To all whom it may concern:

Be it known that I, JOHN S. SORENSEN, a citizen of the United States, residing at Muncy, in the county of Lycoming and State of Pennsylvania, have invented certain new and useful Improvements in Attrition-Mills, of which the following is a specification.

This invention relates to attrition mills, and has for its object the provision of a mill in which the working parts will be reduced to a minimum and which will be capable of running at a high speed for a long continued period without any adjustment of the parts or excessive wear thereon.

Further objects of the invention are to provide a mill of such a construction that the necessity for trammimg, by which much time is lost with the mills now in common use, is entirely obviated; to provide a mill in which the bearings and moving parts will be thoroughly protected against the entrance thereto of flying dust or particles of dirt, so that choking of the mill or burning 25 of the product due to excessive friction will be overcome; to provide means whereby the mill will quickly respond to the entrance of foreign matters between the grinding plates, so as to yield to such foreign substances and thereby prevent injury to the plates, and to provide means whereby the movement of the releasing cam will be limited and the effectiveness of the quick release device thereby increased.

All these stated objects, and such other incidental objects as will hereinafter appear, are attained in such a mill as is illustrated in the accompanying drawings, which are to be taken as a part of this specification.

The invention resides in certain novel features of construction, arrangement and combination of parts which will be hereinafter first fully described and then pointed out more in detail in the appended claims.

In the accompanying drawings: Figure 1 is a central vertical longitudinal section of an attrition mill embodying my present improvements. Fig. 2 is an elevation of the tail end of the machine. Fig. 3 is an enlarged vertical section of the head end bearing. Fig. 4 is a similar view of one of the inner bearings. Fig. 5 is a detail elevation of the end bearing shown in Fig. 3. Fig. 6 is a perspective view of the base. Fig. 7 is a detail sectional view on the line 7-7 of Fig. 6. Fig. 8 is an enlarged longitudinal section of the end thrust bearing and releasing devices. Fig. 9 is a detail vertical section on the line 9-9 of Fig. 8. Fig. 10 is a similar view on the line 10-10 of Fig. 8. Fig. 11 is a similar view on the line 11-11 of Fig. 8. Fig. 12 is a detail section on the line 12-12 of Fig. 11. Fig. 13 is a view showing the relief box in section on the line 13-13 of Fig. 11, and the cam box in elevation. Fig. 14 is a view similar to Fig. 13, but showing the parts in a different position. Fig. 15 is a detail perspective view of the releasing cam. Fig. 16 is an enlarged detail section of the packing ring or stuffing box fitted around the tail end runner against the casing.

In carrying out my present invention, I employ a base 1 which may be of any desired size and is preferably a parallelogram provided along its longitudinal side edges with sockets or brackets 2, through which bolts are inserted to secure the base to a suitable foundation or fixed support. The base is provided at its center with a spout 3 through which the ground material or flour escapes to be stored or subsequently treated, as may be necessary or desirable, according to the nature of the product. Between each end and the spout 3, the base is provided through its top with openings 4 to reduce the weight without affecting the strength of the base, and between the spout and the said openings as well as between the said openings and the ends of the base, reinforcing ribs 5 are formed on its under side so as to reinforce the top plate of the base and also lend additional support to the devices secured upon the same. Upon its upper side, the base is formed with longitudinal ribs or abutments 6, the inner faces or shoulders of which may rise from the base in true vertical planes, as shown at 7, and the several ribs adjacent one side of the base are arranged in exact longitudinal alignment. The series of ribs or abutments are duplicated at each side of the base and each rib preferably rises from a boss 8 on the top of the base, which boss has a perfectly smooth upper face arranged in a true horizontal plane. These bosses form supports or seats for the pedestals presently described, and through the said bosses and the base are vertically disposed openings 9 which are internally threaded to be engaged

by tap bolts inserted through the lower ends of the pedestals to secure the same in position. The pedestals, of which mention has just been made, are clearly shown in Figs. 1 and 2 and consist of approximately triangular blocks or standards having their lower corners 10 planed so as to present square or right angular surfaces which are adapted to fit snugly upon the upper faces of the bosses 8 and against the inner faces of the ribs or abutments 6, as clearly shown in Fig. 2. A number of these pedestals are provided, two being shown to support each runner shaft, and the several pedestals are identical in construction, except that the tail end pedestal is somewhat wider than the others in order to support the end thrust bearing. Upon the sides of the pedestals, at the lower ends thereof, are preferably formed upon standing bosses 11 through which the tap screws 12 are inserted to engage the openings 9 in the base and thereby firmly secure the pedestals in position. In the illustrated embodiment of my invention the outer face or side of the lower corner of the pedestal is disposed at a true right angle to the under face of the same and in a true vertical plane, in order that the several pedestals may be fitted upon the bosses of the base and between the ribs thereon with such nicety and accuracy that subsequent adjustment of the same will be rendered entirely unnecessary. The fastening screws 12 may therefore be turned home, so as to rigidly secure the pedestals in position without the use of any lock-nuts and, when the pedestals are once secured in place, they will remain fixed during the life of the machine. The bosses upon the base will provide seats raised slightly above the plane of the top of the base, while the under sides or lower ends of the pedestals are recessed between their extremities, as shown at 13, so that the contacting surfaces will be reduced to the smallest possible area and possible wear due to any unforeseen vibration of the machine will be obviated. The upper ends of the pedestals are concave so as to present seats 14 to receive the bearings, and these seats, as well as the sides of the pedestals, project laterally beyond the central webs 15, so that openings for the securing bolts may be readily formed through the seats. The bearing shell or housing 16 is substantially a sleeve, the length of which corresponds to the width of the seat 14 and the under side of which is convex so as to fit snugly upon the said seat, as shown most clearly in Figs. 9 and 10. In the under side of the said shell, I provide threaded sockets, indicated at 17, which are engaged by securing screws 18 inserted through the openings in the pedestal, as clearly shown in Fig. 9. By providing bolts or screws 18 at each side of both the longitudinal and transverse centers

of the pedestals and the shells, I secure the shells in place so that movement of the same upon the pedestal will be positively prevented, and, consequently, the necessity for adjustment of the bearings will be overcome. Inasmuch as the bearing shells and the pedestals cannot move relatively to the base, wear upon these parts is positively prevented, and, when the said elements have once been assembled, they will remain fixed in place for all time. As shown in Figs. 1 and 3, the bearing shell for the head end bearing is interiorly threaded throughout its length, and has both ends open, while the bearing shells for the intermediate bearings have smooth bores, and have their inner ends partly closed by internal annular ribs or flanges 19, while the shell for the tail end bearing is extended, as shown at 20, for a purpose which will hereinafter appear.

Referring more particularly now to the head end bearing, it will be noticed that a box or guide 21 is threaded into the shell 16, and this box or guide is provided on its outer end with an axial annular flange 22, provided upon its outer face with a series of lugs or notches 23, which may be engaged by a spanner or similar tool for the purpose of turning the said box or guide into the shell or for adjusting the runner shaft 24 to its proper position in setting up the mill. The bore of this box or guide is smooth for the greater portion of its length and is stepped, as shown at 25, to receive the outer race or ring 26 of an anti-friction bearing, consisting of a pair of concentric rings or races having annular grooves in their opposed circumferential faces and a plurality of balls or rollers 27 seated in the said annular grooves, the exact details of the construction and arrangement being immaterial. The inner end of the box or guide 21 is internally threaded beyond the step 25, as shown at 28, and the cover 29, engaged in the said threaded portion, extends over the inner end of the box or guide and encircles the runner shaft 24 clearly shown in Fig. 3. The inner edge of this cover 29 is provided with an annular groove 30 from which a perforation or other passage 31 leads to the interior of the box. The end of the runner shaft is reduced, as shown at 32, and the inner race or ring 33 of the anti-friction bearing fits upon this reduced end of the shaft and against the shoulder 34 thereby formed, a securing nut 35 being threaded upon the extremity of the shaft and turned up against the said race, so as to clamp the same against the said shoulder, as will be readily understood. As shown in Figs. 3 and 9, this clamping nut is split peripherally at opposite sides of its center and through the split portion locking screws 36 are threaded. After the nut has been turned home against the race 33, these locking

5 screws will be turned up so as to clamp the two portions of the nut together, and thereby cause the nut to bind or lock upon the threads of the shaft, so that the nut will not work loose and permit the bearing to move from its position relative to the end of the shaft. It will be readily noted that the construction and arrangement of the parts described provide a bearing which will resist 10 both the radial and the end thrust of the shaft, so that the shaft will be held in its true horizontal position and axial displacement of the same during the operation of the machine cannot occur.

15 The cover 29 is held against casual rotation by means of screws or bolts 37 inserted through openings provided therefor near the outer edge of the cover and threaded into sockets in the end of the guide or box 21, 20 the edge of the cover overlapping the end of the box or guide, as clearly shown in Fig. 3. By providing these fastening screws or bolts 37, movement of the cover relative to the box or guide is prevented, so that the 25 release of the bearing cannot occur. An oil or grease cup 38 is carried by the box or guide 21, and is mounted in the end of the same so as to offer no interference with the assembling of the box or guide nor with the 30 adjustment of the same within the bearing shell 16.

The inner bearings are similar in construction to the bearing just described, except that the box or guide 21 is omitted, 35 and the anti-friction bearing 39 is mounted within the smooth bore of the shell 16 and fits against the thrust collar 40 provided around the runner shaft 24 and between the anti-friction bearing and the hub 41 of the 40 head runner. The runner shaft is enlarged diametrically to provide a seat for the thrust collar 40 and the bearing 39, and is threaded, as shown at 42, to receive a clamping nut 43 similar in all respects to the 45 clamping nut 35, whereby the bearing 39 is held against the end of the thrust collar. The said thrust collar fits closely within the opening through the annular rib or flange 19, and over the open end of the shell 16 I 50 secure a cover 44, which is provided in its inner edge with an annular groove 45, from which an opening or other passage 46 leads into the interior of the shell. This cover 44 is secured in place by bolts or fastening 55 screws 47 inserted through the cover into the end or edge of the shell, as clearly shown, whereby the cover will be securely held in its position relative to the shell. A grease or oil cup 48 is secured to the top of 60 the shell and leads to the interior of the same, to supply lubricant to the bearing, as shown and as will be readily understood.

The head runner 49 is provided with a hub 41 which is shrunk upon or otherwise 65 secured to the inner end of the head runner

shaft 24 and to the outer side of the said runner is secured a sealing ring 50 which bears against a sealing ring 51 secured to the adjacent opposed side of the spout 52, as shown in Fig. 1, the lower portion of the 70 spout encircling the hub of the runner and being secured rigidly to the shell or casing 53, as will be readily understood. The said shell 53 has an opening in one side to accommodate the end of the spout and the sealing ring 51 secured thereto, and is preferably constructed in sections 54 secured together by locking levers or other devices 55, whereby the casing or shell may be readily 75 assembled around the runners, as will be 80 readily understood upon reference to Fig. 2. The head runner 49 is, of course, equipped with a grinding plate 56, which may be of any well known or preferred design.

The inner bearing for the tail runner 85 shaft 57 is a duplicate of the inner bearing for the head runner shaft, except that the cover is at the opposite side of the center of the mill. The said shaft 57 extends into the casing or shell 53 and the tail end runner 58 90 has its hub 59 shrunk upon or otherwise rigidly secured to the end of the shaft, as will be readily understood. A grinding plate 60 is secured upon the face of the tail end runner 58 and coacts with the grinding 95 plate 56 upon the head runner to grind the grain or other material passing through the mill in the usual manner. Secured to the outer side of the shell immediately adjacent and extending to the hub 59 is a packing box 100 or bearing 61, consisting of two circular plates or rings secured together and to the shell and having their inner edges oppositely beveled, so as to clamp a felt or other washer 62 which will bear upon the hub and thereby prevent the passage of dust through the shell around the hub, and, consequently, counteract the tendency of dirt to accumulate around the hub and create excessive 105 friction which has been encountered in mills 110 previously constructed. It will be readily observed that the construction of this box permits the felt or other washer to be readily renewed when worn or to be adjusted so as to take up the wear as long as there is 115 sufficient fabric left to be held by the circular plates or rings. Band pulleys 63 are secured upon both runner shafts intermediate the ends thereof, so that motion may be imparted to the said shafts to operate 120 the mill, as will be readily appreciated.

The shell or housing 16 for the tail end bearing, as before stated, is provided with a cylindrical extension 20 having a central opening through which a step box 64 projects and the bore of this extension is angular, preferably hexagonal, to receive the angular head 65 of the said step box, whereby the step box may be permitted to move longitudinally of the shell, but will be held 130

against rotation therein. The said step box is also provided with a longitudinal groove 66 in its bore, adapted to be engaged by a pin or projection 67 on the center guide plug 68, whereby rotation of the said plug in the step box is prevented, while relative longitudinal movement is permitted. The bore of the extension or shell 20 is smooth throughout, but the end of the step box is 10 threaded to be secured in the end of a relief box 69, as shown. Between the outer end of the shell and the head 65 of the step box is coiled an end-thrust spring 70 which normally holds the step box inwardly away 15 from the end of the shell and the relief box against the end of the shell. An excessive increase of pressure upon the spring, however, as by the entrance of an excessively large and hard substance between the grinding plates, will cause the relief box to move 20 away from the shell to accommodate the axial movement of the runner shaft. The tension of this spring may be adjusted by rotating the relief box whereupon the 25 threaded connection of the same with the step box, will effect a longitudinal movement of the latter and compress the spring, a single revolution of the relief box being sufficient to effect a perceptible increase in 30 the tension of the spring. After adjustment, the relief box is held against rotation relative to the shell by a pin or key 71 inserted through aligned openings in lugs 72 on the shell and the box, as clearly shown, 35 and as will be readily understood.

The center guide plug 68 has its inner end expanded, as shown at 74, to form a head or piston fitting within the expanded bore or chamber 74 of the shell, and the said head 40 or piston is provided at its top with a groove or opening 75 which will permit the air within the chamber to pass from one side of the piston or head to the opposite side thereof to equalize the pressure on the two faces 45 of the piston, and thereby avoid choking or impeding the movement in the operation of the device. A grease or oil cup 76 is mounted on the upper side of the shell immediately over this opening 75, and the 50 lubricant from the said cup will pass on to the piston and find its way through said opening to the bearing 77 within the shell, as will be readily understood, the pin 67 serving as a stop to prevent the escape of 55 the lubricant to and through the outer end of the shell. The said bearing 77 is preferably of the type previously described, and is held upon the end of the tail runner shaft 57 by means of a clamp nut 78 holding the 60 inner race against an annular shoulder 79 on the shaft, as clearly shown in Fig. 8. The outer race of this bearing has an external diameter which will permit it to fit snugly within the smooth bore or chamber 74 of the shell and this race is held by and between

the annular edge of the head or piston 73 and a safety spring guide sleeve 80 mounted within the said chamber and encircling the end of the runner shaft. This sleeve 80 is formed with an annular recess or socket 81 70 which receives one end of a safety spring 82 coiled around the shaft and having its opposite end bearing against the cover plate 83 secured to and extending across the inner end of the shell, as clearly shown in Figs. 1 75 and 8. This cover is provided with an annular groove 84 in its inner edge and an opening 85 leading therefrom into the chamber 74, and is also provided with a central annular rib or collar 86 which fits closely 80 around the runner shaft and serves as a support for the end of the safety spring.

The outer end of the relief box 69 is closed by a removable cap 87 through which is threaded a tail screw 88 equipped with a hand wheel 89 and a jam nut 90. The inner end of this screw 88 bears against the outer side of a cam box 91 which is mounted concentrically within the relief box 69 and is spaced therefrom to reduce friction by longitudinal projections or spacing ribs 92 on its outer surface. In the sides of this box, at diametrically opposite points of the same, I form open-ended notches or slots 92' which register with slots 93 in the sides of the relief box, and upon the inner face of the back wall of the cam box I provide a rib or bearing strip 94. Between this bearing strip or rib 94 and the outer end of the center guide plug 68, I arrange a releasing 95 cam 95, which is mounted upon a cam shaft 96, the ends of which project through the slots 93 in the relief box and are mounted to rotate within the same. Longitudinal movement of the cam shaft is prevented by means 100 of an annular shoulder or enlargement 97 on one end of the same and a retaining disk or stop 98 secured to the opposite end thereof, said collar and stop bearing against the opposite outer sides of the relief box, as 105 shown most clearly in Fig. 11. An operating lever 99 is secured to one end of the cam shaft, so that the operator may readily throw the said shaft to the released or the holding 110 position, when such action is necessary. The cam 95 is substantially an elliptical block so arranged as to provide opposite parallel faces furnishing straight bearings against the rib 94 and the end of the center guide plug, as clearly shown in Fig. 12, two of 115 said faces being at a greater distance apart than the intervening two faces, and said more distant faces being curved concentric with the cam shaft, as clearly shown, the said curved faces being indicated at 100 and 120 101, while the intervening faces are indicated at 102 and 103. One end of the cam is formed with a cylindrical trunnion 104, while at the opposite end is a cam trunnion 105 having outwardly projecting diametri- 125

5 cally opposite stop shoulders or corners 105', the extremities of which are at a greater distance from the center of the cam shaft than are the sides of the trunnion. The 10 purpose of this peculiar construction of the cam trunnion is clearly shown in Figs. 13 and 14. When the cam 95 is arranged as shown in Figs. 1, 8 and 13, to spread apart the cam box 91 and the center guide plug 68, the cam trunnion 105 will occupy the position shown in Fig. 13, in which the greatest radius of the cam trunnion will incline upwardly toward the outer end of the mill, in which position, if it be attempted to move 15 the lever downward toward the end of the mill, the corners 105' of the cam trunnion will be brought against the upper and lower walls of the notch 92' in the cam box, and, consequently, rotation of the cam in that direction will be prevented. Movement of the 20 cam in the opposite direction, however, will be permitted, owing to the fact that the edges or sides of the cam trunnion between the extended points 105' are curved on a 25 radius which terminates short of the walls of the notch and, consequently, the cam shaft may be turned to the position shown in Fig. 14, in which the greatest radius of the cam trunnion will incline downwardly toward 30 the rear end of the mill. The movement of the cam beyond the position shown in Fig. 14 will be prevented by the extended corners of the cam trunnion coming into contact with the walls of the notch 92' opposite 35 the walls previously engaged by the said corners, respectively, and it will therefore be seen that the cam shaft can rotate only through one quarter of a circle, and, consequently, it is impossible for the operator to 40 throw the lever through an arc greater than that necessary for the proper operation of the releasing device or in the wrong direction. It will be readily appreciated that if the cam could be swung through one-half a 45 revolution, the relative positions of the relief and step boxes would be the same as that occupied previous to the movement, so that the releasing devices would prove ineffective, and considerable difficulty and trouble has 50 been occasioned heretofore by the operator imparting excessive movement to the releasing cam. By my present construction this excessive movement is positively prevented.

55 It will be readily observed from the foregoing description, taken in connection with the accompanying drawings, that when my mill has been set up in its operative position, the runner shafts will be supported positively and fixedly in axial alinement, so that 60 the runners will be maintained with their working faces in parallel relation through the life of the machine. It will be observed that my mill dispenses with the elongated bearings heretofore considered necessary and 65 substitutes therefor short bearing supports

in which the frictional engagement is reduced to a minimum so that the radial and end thrust of the runner shafts will be effectively taken up without creating a large amount of friction. As the number of parts 70 is so greatly reduced and the moving points of support are so few, the frictional resistance is practically eliminated, and, consequently, wear upon the shafts or their supports is overcome, so that the axial alinement 75 of the shafts is preserved, and no necessity for trammimg the mill will arise. In my present mill, the only adjustment required after the mill has been set up is the longitudinal adjustment of the runner shafts 80 to compensate for wear upon the grinding plates and upon the sealing rings. To accomplish this adjustment of the head runner shaft, the box or guide 21 is rotated so that it will ride longitudinally in the end shell 16 85 by reason of its threaded connection therewith, and this longitudinal movement of the said box or guide will be transmitted to the runner shaft through the bearing 26, inasmuch as the said bearing is clamped to the 90 box or guide by the cover 29 and also clamped to the runner shaft by the nut 35. As the anti-friction bearing 39 of the inner support or bearing is mounted within a smooth-bored shell, the said bearing will 95 readily follow the movement of the shaft within the said shell, so that the engagement and relative positions of the runner hub, the thrust collar, and the clamping nut relative to the said bearing will not be disturbed. A 100 similar adjustment of the tail runner shaft may be effected by rotating the tail screw 88, this action causing said screw to move the cam box 91 longitudinally of the relief box, and this movement will be transmitted 105 directly to the runner shaft through the center guide plug and the bearing 77. As the safety spring acts through its guide sleeve to hold the bearing against the head of the center guide plug, the several parts 110 will follow the movement of the tail screw in either direction. When the desired adjustment has been effected, the jam nut 90 is turned home to hold the parts in their adjusted relation. Should the material pass 115 into the space between the grinding plates in an excessive quantity, the resistance of such substance to the action of the grinding plates, aided by the safety spring, will force the runners slightly apart against the tension of the end thrust spring 70, so that the 120 said substance will gradually work out through the mill without injuring the working parts, the relief box moving outwardly under the increased pressure applied thereto 125 through the bearing 77, the center guide plug, the relief cam, and the parts coacting therewith. Should some foreign matter pass between the grinding plates and jar the mill, the operator will throw the lever 99 up 130

to a vertical position, which will cause the releasing cam to assume the position shown in Fig. 14, whereupon the safety spring will at once expand and move the runner shaft outwardly by the pressure exerted upon the shaft through the guide sleeve 80, the bearing 77 and the center guide plug 73. The runners will thus be separated sufficiently to permit the foreign substance to pass from the mill; the cam being subsequently returned to its normal position, indicated in Figs. 1, 8 and 13, and thereby moving the several parts in opposition to the safety spring to return the runner shaft with its attached runner to its working position. It will thus be seen that I have provided means whereby the end thrust upon the runner shaft will be taken up while axial movement of the said shaft is permitted, so that the runners will be held to their work but injury to the grinding plates by foreign substances will be prevented, and have also provided means whereby the moving of the grinding faces back to their working positions, before the foreign matter has been discharged, is prevented.

The moving parts of my mill are preferably lubricated by thick lubricant fed into the bearing chambers or supports from grease cups mounted on the said supports. This lubricant has a well known tendency to work around a moving shaft or other element, and by reason of this tendency will travel along the shaft toward the cover plates. When it reaches the grooves in the inner edges of these plates, centrifugal action occurs, so that the lubricant is caught in and travels around the said grooves and then escapes therefrom through the openings at the lower portions of the same, and is consequently returned to the chambers within which the shaft rotates. Loss of lubricant and collection of the same upon the outer surfaces of the mill is thereby prevented and, consequently, the collection of grit upon the shaft and the bearings is avoided, so that wear upon the shafts and forcing of the same from their axial positions is obviated. It is clear from the drawings that the bearings are completely housed and protected against the entrance of flying particles of dust so that smooth easy running of the mill is assured.

Having described my invention, what I claim as new and desire to secure by Letters Patent is:

1. In an attrition mill, the combination of supporting pedestals having bearing seats formed in their upper ends, bearing shells rigidly secured in said seats, bearings mounted slidably within the shells, and a shaft extending through the shells and mounted in said bearings.

2. In an attrition mill, the combination with a plurality of alined supports, of a

bearing carried by the upper end of each support and adapted to resist thrusts from two directions, and a runner shaft extending through and supported by said bearings.

3. An attrition mill having its runner shaft mounted in a plurality of bearings spaced apart and each arranged to resist both radial and end thrust.

4. The combination, in an attrition mill, of a casing, a runner having its hub extending through the side of the casing, a pair of circular plates secured to the outer side of the casing, and a washer secured between said plates and extending to and fitting around the end of the hub.

5. In an attrition mill, the combination of a bearing shell having an axial extension at its outer end, a step box slidably mounted in said extension, an end thrust spring coiled around the step box and bearing against the head of the same and the end of the extension, a relief box secured upon the outer end of the said step box, a guiding plug extending through the said step box and having an enlarged inner end, a runner shaft having its end entering the said shell, a bearing secured on the end of the said shaft and fitting against the enlarged end of the guide plug, a guide sleeve on the shaft fitting against the said bearing, a spring bearing upon the said sleeve and the end of the shell, and means within the relief box whereby the guide plug may be held to the end of the shaft or may be permitted to move quickly outward in the shell.

6. In an attrition mill, the combination of a runner shaft, a shell surrounding the end of the shaft, a spring in the shell beyond the end of the shaft tending to hold the shaft in an inner position, a lesser spring within the shell around the end of the shaft tending to move the shaft outward, and means for releasing the greater spring to permit the lesser spring to act.

7. In an attrition mill, the combination of a runner shaft capable of longitudinal movement, a casing inclosing the end of the shaft, means for holding the shaft normally inward, means tending to move the shaft outward, and controlling devices whereby the shaft may be released from its inner position and moved outward, said means which tend to move the shaft outward being housed within the casing.

8. In an attrition mill, the combination of a runner shaft capable of longitudinal movement, a bearing secured around said shaft, an end thrust spring, a safety spring, and intermediate devices whereby said springs act upon the bearing in opposition to each other.

9. In an attrition mill, the combination with a runner shaft, and an end thrust bearing therefor, of a relief box, a cam box mounted in the relief box and having lon-

5 longitudinal slots in its sides, a cam bearing upon said box and a member of the end thrust bearing to connect or release the same, and trunnions at the ends of said cam playing in the slots in the cam box, one of said trunnions having unequal radii and its longest radius being greater than the width of the slot in which it plays.

10. In an attrition mill, the combination with a relief box, and a guide plug having its end within the same, of a cam box having a slot in its side and mounted within the relief box, a cam within the said cam bearing against the same and the end of the 15 guide plug, a cam trunnion at one end of the cam playing in the slot in the side of the cam box and adapted to impinge against the walls of said slot whereby the movement of the said trunnion and the cam will 20 be limited.

11. An attrition mill having in combination a plurality of slidably mounted bearings spaced apart and each arranged to resist both radial and end thrust, a runner- 25 shaft mounted in said bearings, and means for adjusting said bearings, whereby said shaft may be adjusted longitudinally.

12. In a grinding mill, the combination with a base frame, standards thereon, longitudinally movable bearings mounted on adjacent standards, a shaft journaled in said bearings, an axially alined shaft mounted on the other standards, and grinding disks on the inner adjacent ends of said 35 shafts; with means for moving said movable bearings longitudinally on the standards to move the shaft bodily and separate the disks without disturbing the grinding adjustment of said shaft in its bearings.

40 13. In a grinding mill, the combination with a base frame, standards thereon, longitudinally disposed shafts mounted on said standards, and grinding disks on the inner adjacent ends of said shafts, bearings for 45 said shafts mounted on the standards, each shaft being supported on two standards, both bearings for one of said shafts being slidably longitudinally on their standards; with means adapted to engage one of said 50 shafts to move it and thereby the shaft and its other bearing and its disk longitudinally of the frame without disturbing the grinding adjustment of said shaft in its bearings.

55 14. In a grinding mill the combination of a base, axially alined standards thereon, a housing, bearings on said standards, a pair of axially alined shafts mounted in the said bearings at opposite sides of the housing and extending into the housing, grinding disks on the ends of said shafts within the housing, the bearings for one of said shafts being slidably mounted on their standards 60 and the shaft supported by said movable bearings being rotatably but normally lon-

70 gitudinally immovably journaled therein; with means for simultaneously shifting both said bearings longitudinally of the base and thereby moving the shaft longitudinally without disturbing the grinding adjustment of said shaft in its bearings.

15. In a grinding mill, the combination of a housing formed with an extension or neck, grinding heads, a rotary shaft carrying one of the heads and extending into the housing, said shaft being movable longitudinally in opposite directions to carry its grinding head to and from the opposing head, a spring arranged within the housing and acting to urge the shaft in a direction 80 to separate the heads, and a second spring of stronger tension arranged in the neck of the housing and acting to urge the shaft in a contrary direction.

16. In a grinding mill, the combination of a fixed frame or housing, grinding heads, a shaft carrying one of said heads and movable longitudinally in a direction to carry its head away from the opposing head, releasable means for holding the heads in 90 grinding relation to each other, an anti-friction bearing between the shaft and frame, said anti-friction bearing comprising an inner member fixed to the shaft, an outer non-rotatable member movable longitudinally in the housing, and a series of interposed rolling elements serving to hold said bearing members against relative movement longitudinally, and a spring acting to urge the outer bearing member longitudinally in 100 the direction of the longitudinal movement of the shaft to separate the heads when said means are released.

17. In a grinding mill, the combination of a frame or housing, grinding heads, a rotary shaft carrying one of the heads and movable longitudinally in a direction to separate its head from the opposing head, releasable means for holding the heads in 105 grinding relation to each other, a non-rotatable member mounted to slide longitudinally in the housing with the shaft, a non-rotatable sleeve mounted in the housing and engaged by and movable longitudinally with said member, and a spring engaging between the 110 housing and said sleeve and tending to shift the shaft in a direction to separate the heads when said means are released.

18. In a grinding mill, the combination of a frame or housing, grinding heads, a rotary shaft carrying one of the heads and movable longitudinally to carry its head away from the opposing head, a non-rotatable member mounted in the housing to move longitudinally with the shaft, a spring between the housing and said member tending to separate the heads, a second non-rotatable member mounted to slide longitudinally in the housing and engaged by the first mentioned member, and a spring acting to urge said sec- 120 125 130

ond member longitudinally so as to move the heads together.

19. In a grinding mill, the combination of a frame or housing, grinding heads, a rotary shaft carrying one of the heads and mounted in the housing to move longitudinally to carry its head away from the opposing head; a non-rotatable member mounted to move longitudinally in the housing with the shaft, 5 a second longitudinally movable member engaged by the first member and provided with an axial extension, and means for yieldingly supporting the end thrust of said axial extension.
- 15 20. In a grinding mill, the combination of a frame or housing, grinding heads, a rotary shaft carrying one of the heads and mounted in the housing to move longitudinally to carry its head away from the other head, a 20 non-rotatable annular member mounted in the housing exterior of the shaft and movable longitudinally with the shaft, a second non-rotatable member engaged by the first mentioned member and mounted to move longitudinally and means for yieldingly 25 supporting the end thrust of said second member.
21. In a grinding mill, the combination of

a frame or housing, grinding heads, a rotary shaft carrying one of the heads and movable longitudinally to carry its head away from the opposing head, a non-rotatable member exterior to the shaft in which the shaft is rotatably mounted, said member being movable longitudinally with the shaft, and yielding means coöperating with said member and tending to urge the same and shaft in a direction to move the grinding heads together. 30

35 22. In a grinding mill, the combination with a base frame, longitudinally disposed shafts mounted thereon and opposed grinding disks on the inner adjacent ends of said shafts, a set of independently adjustable bearings for one of said shafts; said adjustable bearings being simultaneously slidable 40 with the shaft longitudinally of the base to permit said shaft and its disk to be moved longitudinally of the frame to bodily separate the disks.

45 In testimony whereof I affix my signature, in presence of two witnesses.

JOHN S. SORENSEN.
